UNITED STATES PATENT OFFICE.

CHARLES E. BLUE, OF WHEELING, WEST VIRGINIA.

MACHINE FOR THE MANUFACTURE OF PRESSED AND BLOWN GLASSWARE.

No. 828,180.

Specification of Letters Patent.

Patented Aug. 7, 1906.

Application filed August 23, 1902. Serial No. 120,828.

To all whom it may concern:

Be it known that I, CHARLES E. BLUE, a citizen of the United States, residing at Wheeling, in the county of Ohio and State of West Virginia, have invented new and useful Improvements in Machines for the Manufacture of Pressed and Blown Glassware, of which the following is a specification.

My invention relates to improvements in machines for the manufacture of pressed and blown glassware which will be fully described hereinafter and pointed out in the claims.

In the accompanying drawings, Figure 1 is a side elevation of my improved machine, one of the molds being shown in vertical section with the blow-head in operative position. Fig. 2 is a vertical sectional view taken at right angles to Fig. 1, the presser-head and plunger being shown in operative position. Fig. 3 is a top plan view of my improved apparatus. Fig. 4 is a detached view showing the blowing attachment operative independent of the presser-head and plunger. Figs. 5, 6, and 7 are sectional views showing a modification in the construction of the bottom of the press-cavity of the combined press and blow molds.

Referring now to the drawings, 1 is a column, suitably supported at its base, and 30 rotatably supported by this column is a table 2. This table 2 carries a plurality of molds 11, each one of which is provided with a press-cavity 15 and a blow-cavity 14. These molds are vertically centrally divided and 35 open horizontally, being hinged together at the point 2' and provided with suitable handles 3', by means of which they are opened and closed. Arranged horizontally above and at the side of these molds are horizontal 40 neck-ring-supporting tracks 13, which are supported by suitably arranged vertical standards 13'. Supported by and slidably upon these tracks are the neck-rings 10, whereby the neck-rings which support the 45 pressed blanks are movable from the press-cavity of the mold to and over the blow-cavity.

A cylinder 4 is located at the upper end of the column, which is arranged with passages 50 *a*, communicating with opposite ends thereof in the same manner as in the cylinder of a steam-engine. The outer ends of these passages *a* communicate with a valve-chamber *b*, in which is located an oscillating valve *d*, 55 which controls the passage of fluid under pressure through these passages to opposite

ends of the cylinder for the purpose of moving the piston *f* therein, as is well understood. A handle *e* is carried by the valve *d* for controlling it, and this handle projects downward within reach of the operator. A plunger-rod 6 is attached to the piston *f*, and a plunger 8 is carried by the lower end thereof and is adapted to enter the press-cavity of the mold that may be located thereunder. An arm 20 projects horizontally from the piston-rod, and the outer end of this arm supports and carries a suitable blow-head 23. A tube 21 communicates with the blow-head, and a flexible tube 22 is connected with the tube 21, permitting the blow-head to be raised and lowered. Since the blow-head is connected with the plunger-rod 6 by the arm 20, as before explained, it will be understood that the blow-head is moved up and down in unison with the plunger.

By reference to Fig. 3 it will be noted that preferably five molds are used and that as the table 2 is rotated these molds will successively occupy the "charging," "pressing," "blowing," "discharging," and "cooling" positions designated in this view.

In Fig. 2 the means for locking the table at the proper points for operation is plainly illustrated, and consists of a vertically 85 spring-actuated rod 16, having its upper end properly shaped to enter cavities in the under side of the table. This rod slides in a bracket 18 and is operated by a suitable handle 17.

As previously stated, the blow-head in Fig. 1 is shown connected with the plunger-rod and moved thereby. In Fig. 4, however, the blow-head is shown separate from the plunger and slides vertically in a horizontal bracket projecting from the upper end of the column 1. A spring 24 serves to hold the blow-head 23 normally upward, and it is moved down to the blowing position against the tension of this spring through the medium of a horizontally-projecting pivoted handle 25.

If desired, the press-cavities may have a movable bottom *i*, as shown in Figs. 5, 6, and 7, which is for the purpose of preventing the formation of a seam across the bottom of the finished article. In this instance the bottom is actuated through the medium of a sliding handle *j*, which is provided with a cam-slot *k*, through which passes a pin *m*.

In operation the neck-ring is opened at the discharging-point and molten glass is placed

in the press-cavity of each mold and the mold is closed when at the charging-point, Fig. 3, and the table 2 is rotated to carry the charged mold to the pressing-point. The plunger is 5 then caused to move therein through the movement of the handle *e* for the purpose of forming a pressed blank to be blown into the finished article in the blow-cavity. The mold is then opened and the pressed blank is 10 supported by the neck-ring, and the neck-ring is moved on its supporting-track 13 until the blank is positioned within the blow-cavity, after which the mold is closed, glass is dropped in the press-mold at the charging-point, and the table rotated one-fifth of a revolution. Another pressing operation is performed and at the same time a blowing operation is effected. As the table is moved 15 around, each mold assumes the several positions indicated in Fig. 3, where the charging, pressing, blowing, discharging, and cooling is effected.

From this description it will be understood that the table 2 is, in effect, generically 20 an endless carrier, which is provided with a plurality of molds, each mold having a press and a blow cavity and preferably each mold provided with a neck-ring-supporting track upon which the neck-ring is adapted to be 25 moved from one cavity of the mold to the other.

Stops will be provided on the neck-ring track for the purpose of limiting the movement of the neck-ring and insuring the proper 30 centralizing of the neck-ring in respect to the press and blow cavities.

Attention is directed to the interior formation of the press-cavity, it being enlarged centrally with its mouth or inlet relatively 35 smaller. This construction enables me to get more glass in a certain-sized top opening than is possible where the cavity tapers gradually from top to bottom in the usual manner.

40 In Fig. 1 the blow-head is connected with the presser-head and is automatically worked, as before stated, and in Fig. 2 I show another form of automatic connection. This consists of a lever 40, which has its outer end 45 pivotally connected with the spring-actuated rod 16, and this rod is adapted to be operated by either the hand-lever 17 or the foot-lever 43. A rod 41 has its lower end pivotally connected with the lever 40 and its upper end 50 pivotally connected with the inner end of an intermediately-pivoted lever 42, located at the upper end of the column 1. The outer end of the said lever 42 is adapted to actuate the tube 21, which carries the blow-head, so 55 that when the spring-actuated rod is permitted to engage the table after it has been moved to carry the molds to proper position the blow-head is lowered and engages the mouth of the blow-mold, as is well understood 60 by those skilled in the art.

Having thus described my invention, what I claim, and desire to secure by Letters Patent, is—

1. A machine for the manufacture of glass-ware, including a rotatable table, a plurality 70 of molds located thereon, each mold having a press and blow cavity, a neck-ring track located at each side of the mold and extending in a direction longitudinally of the mold-cavities, and a neck-ring slidably supported by 75 each of said pair of tracks and adapted to coact successively with both cavities.

2. A machine for the manufacture of glass-ware, including a rotatable table, a plurality 80 of relatively non-movable molds carried by said table, each mold having a press and a blow cavity, a neck-ring track arranged at the side of each mold and extending in a direction longitudinal the arrangement of the mold-cavities, and a slidable neck-ring sup- 85 ported by said track and adapted to be moved on the track to coact with each cavity of the mold.

3. A machine for the manufacture of glass-ware, including a rotatable table, a plurality 90 of molds carried by the table, each mold having a press and a blow cavity, radially-ar- 95 ranged neck-ring tracks located at the side of each mold and extending in a direction longitudinal the arrangement of the mold-cavities and a neck-ring slidably supported by 95 said track and adapted to coact with the press and blow cavities.

4. A machine for the manufacture of glass-ware, including a rotatable table, a plurality 100 of molds connected with the table at fixed points, each mold having a press and a blow cavity, the press-cavities of all of said molds being located in the arc of one circle, and the blow-cavities located in the arc of a different 105 circle, a blow-head arranged at a point in the arc of the circle traveled by the blow-cavities, a plunger located at a point in the arc of the circle traveled by the press-cavities and a 110 slidable neck-ring adapted to coact with both cavities of the molds.

5. A machine for the manufacture of glass-ware, including a mold having a press and a blow cavity, a neck-ring support extending 115 in a direction longitudinally of the mold-cavities, and a neck-ring slidably supported by said support and adapted to coact successively with said cavities.

6. A machine for the manufacture of glass-ware, including a rotatable table, a plurality 120 of molds thereon, each mold having a press and a blow cavity, radially-arranged neck-ring tracks extending longitudinally the mold-cavities, and a neck-ring slidably supported by 125 said tracks and adapted to coact with said cavities.

7. A machine for the manufacture of glass-ware, including a mold having a press and a blow cavity, and a slidable neck-ring adapted to coact with said cavities. 130

8. A machine for the manufacture of glass-
ware, including a rotatable table, a plurality
of molds located thereon, each mold having a
press and blow cavity, a radially-arranged
neck-ring track located at each side of the
mold and extending longitudinally of the
mold-cavities, and a neck-ring slidably sup-
ported by each of said pair of tracks and
adapted to coact successively with both cavi-
ties.

9. A machine for the manufacture of glass-
ware, including a rotatable table, a plurality
of mold's located thereon at fixed points, each
mold having a press and a blow cavity; a

neck-ring support independent of said rota- 15
table table and arranged to extend in a direc-
tion longitudinal the two mold-cavities of
each mold when the table is rotated to bring
a respective mold in operative position, and a
neck-ring slidably supported by said support 20
to coact successively with said mold-cavities.

In testimony whereof I have hereunto set
my hand in the presence of two subscribing
witnesses.
